MOUNTING ASSEMBLY

Carl Vincent Erickson, Kansas City, Kans., assignor to Speer & Koenig, Kansas City, Mo., a copartnership composed of Joseph G. Speer and Herbert G. Koenig.

Application November 4, 1946, Serial No. 707,730

7 Claims. (Cl. 74—63)

1.

This invention relates to mounting assemblies and more specifically to devices having a plurality of angularly arranged shafts and rollers particularly adapted for use with radio direction finders.

In the field of radio direction finders, wherein a rotatable directional antenna is utilized, having a prime mover adapted to oscillate the antenna about a vertical axis, it has been found desirable to develop a device for removing continual irregular variations of "hunting" inherent in such assemblies. It is well known by those skilled in the art that radio direction finders, having means for automatically controlling the direction of rotation of the directional antenna through control means for the prime mover, therefore in accordance with the strength of the incoming signal, produce motion irregularities or "hunting." An obvious arrangement or device for accomplishing this elimination or reduction of motion irregularities would consist of a system of masses or flywheel and spring combinations. A somewhat dissipative load is usually required and the mass may be reduced or eliminated if the spring or springs work into a suitable load, i.e. a load whose resistance varies in magnitude as velocity varies. Serious defects have been found through use of such methods of attenuating "hunting" especially where limitations of damping, space and mass exist.

It is the primary object of this invention, therefore, to provide a mounting assembly or device for removing continual irregular variations, which is free from the above described defects in that the same is provided with certain positive drive characteristics to the end that the load carried thereby does not influence its operation.

An important object of this invention is to provide a mounting assembly which derives its operating power from the "hunting" of the motions which it attenuates rather than through the employment of an auxiliary drive source.

Another important object of this invention is to provide a mounting device having a plurality of shaft and roller assemblies cooperating to reduce to a minimum or zero the rotational movement which the drive shaft imparts to the driven shaft upon reversal of the direction of rotation of the drive shaft and thence to progressively increase the speed of rotation of the driven shaft in the opposite direction to a predetermined rate.

A further object of this invention is to provide in a mounting assembly, having a drive shaft and a driven shaft, a pair of rollers disposed in mutual peripheral, frictional contact and each simultaneously revolvable on an axis perpendicular

2.

to its axis of rotation as the same rotates, to the end that one of said rollers is driven by the other roller in response to rotation of the drive shaft and the driven roller tends to seek a new relative axial alignment with the drive roller each time the direction of rotation of the drive shaft is reversed, thereby removing irregular variations in the rotational motion of the driven shaft.

A still further object of this invention is to provide a mounting assembly having a roller which is simultaneously rotated and revolved about an axis perpendicular to its axis of rotation in response to rotation of a drive shaft in either direction, and a second roller likewise simultaneously rotatable and revolvable in response to the revolving motion of the first roller, all to the end that the second roller tends to seek one of two positions of relative axial alignment with the first roller, depending upon the direction of rotation of the drive shaft, and the driven shaft thereby progressively increases in speed of rotation as one of such axial alignment positions is approached.

Additional objects of this invention which relate more specifically to the purely structural details thereof, include the manner of transmitting simultaneous rotational and revolving motion to the drive roller from rotational movement of the drive shaft; the way in which the driven roller is mounted to receive such simultaneous revolving and rotational motion; the manner in which the motions present in the driven roller are transmitted into rotational movement in the driven shaft; and the manner in which the speed of rotation of the driven shaft is progressively decreased and then increased upon reversal of the direction of rotation of the drive shaft through the unique disposition and mutual engagement of the drive and driven shafts.

Many minor objects will be made clear or become apparent during the course of the following specification, referring to the accompanying drawings, wherein,

45. Fig. 1 is a side elevational view of the mounting assembly made in accordance with my present invention, parts being broken away for clearness.

50. Fig. 2 is a side elevational view thereof taken at a right angle to Fig. 1, other parts being broken away for clearness in detail of construction.

Fig. 3 is a cross-sectional view taken on line III—III of Fig. 1.

55. Fig. 4 is a cross-sectional view taken on line IV—IV of Fig. 1; and

Fig. 5 is a schematic detailed top plan view of the rollers per se, showing their relative positions and illustrating their respective revolving movements.

While it is contemplated that the mounting assembly about to be described be used primarily with rotatable antennas used in radio direction finders, due to the necessity of eliminating irregular motions in the antenna which emanate from constantly changing motions in the prime mover therefor, it is understood that this assembly may well be used in many other fields where it is desired to transmit or indicate axial motions or positions from a driving element to a driven element and remove irregularities in motion inherent in the driving element before such axial motion is transmitted to the driven element.

In the drawings a framework, generally designated by the numeral 10, comprises a cylindrical housing 12 having the ends thereof closed by a pair of heads 14 and 16, which are held in closing position by a pair of threaded bolts or the like 18. Heads 14 and 16 have bearings 20 and 22 for mounting a driven shaft 24 and a drive shaft 26 respectively. Drive shaft 26 may be rotated by any suitable prime mover (not here shown) capable of rotating the same in either direction, and driven shaft 24 is likewise rotatable in either direction. Shafts 24 and 26 are disposed in substantial axial alignment and the proximal ends thereof are in spaced apart relation as is clear in Figs. 1 and 2. Drive shaft 26 carries a substantially U-shaped yoke 28 at the innermost end thereof, which yoke is preferably integral with shaft 26, and the legs 30 and 32 thereof each have an opening 34 for receiving a pair of bearings 36. These bearings 36 journal a shaft 38 which shaft 38 in turn has a roller 40 fixed thereto. When assembled this roller 40 is disposed substantially midway between legs 30 and 32 of yoke 28. It is clear, therefore, that rotation of drive shaft 26 will cause shaft 38 and roller 40 carried thereby to revolve about an axis in alignment with the axis of rotation of drive shaft 26. A pair of bearings 42 and 44 disposed near the outermost ends of shaft 38 each carry rollers 46 and 48 respectively. Each of these rollers 46 and 48 is free to rotate on shaft 38 in one direction through the medium of an annular ring 50, seated in a cavity 52 formed in head 16. This head 16 has a continuous annular cavity 54 within which is disposed a number of springs 56, each having one end thereof bearing against a stub pin 58, mounted in the lowermost edge of ring 50. A one direction automatic clutch is provided for each of the rollers 46 and 48, one being a left hand clutch and the other a right hand clutch, which may be constructed in one of several ways. The undirectional clutches which have been chosen for illustration, constitute a pair of coiled springs 60 and 62, each having a diameter to provide a close fit about the shaft 38. One end of each of the springs 60 and 62 is fixed to rollers 46 and 48 respectively to the end that one direction of rotation of each of the rollers will result in a slight friction between the springs and the shaft 38 and will cause the spring to unwind slightly thereby reduce the friction and permitting the same to slip in that direction. In the other direction of rotation of a given roller 46 or 48, friction between its spring and shaft 38 causes the coil spring to tighten its coils and bind on the shaft 38, thus giving a positive drive in that direction. In other words, in one direction of rotation of the drive shaft 26, roller 48 will drive

shaft 38 but the roller 46, rotating in the opposite direction through the medium of frictional contact thereof with ring 50 will slip on shaft 38 because of the inoperative action of its spring 60. 5 When the direction of rotation of the shaft 26 is reversed, roller 46 will drive shaft 38, because of the frictional contact or tightening of its coil spring 60 about shaft 38 but the spring 62 will slip and permit free rotation of its roller 48. It is obvious therefore, that shaft 38 and its central roller 40 will always rotate in only one direction irrespective of the direction of rotation of shaft 26. It is also evident from the construction just described that rotation of shaft 26 in either direction will cause roller 40 to simultaneously revolve and rotate.

The construction of the associated parts of driven shaft 24 is substantially the same as described with respect to drive shafts 26. A yoke 64 integral with the innermost end of shaft 24 rotatably carries a shaft 66 through the medium of bearings 68, between which is disposed a roller 70 rigidly fixed to shaft 66. Also rigidly fastened to the shaft 66 at one end thereof is roller 72, which runs on a circular track 74 secured to head 14. It is also desirable to provide a freely rotating roller 76 at the opposite end of shaft 66, also disposed to run on track 74. This will balance the forces opposing axial thrust of shafts 26 and 24 but will have no effect on their respective rotational movements. It is clear in Figs. 1 and 2 that rollers 40 and 70 are in peripheral, frictional contact and are held in such engageable relation through the action of springs 56, which springs 56 also hold rollers 72 and 76 in frictional contact with the circular track 74 on head 14. When revolving and rotating motion is imparted to roller 40 through rotation of drive shaft 26, such movement will be transmitted to roller 70, which 20 is also revolvable about an axis in substantial alignment with the axis of rotation of driven shaft 24 or on an axis perpendicular to its own axis of rotation. When roller 70 is rotated by roller 40, roller 72 will run on track 74, changing the axial direction of rotation of shaft 66 and roller 70 carried thereby. Roller 40 contacts roller 70 with moderate pressure to the end that rotation of roller 70 may occur, the amount depending upon the relative axial position of rollers 40 and 70. Rotational motion applied to drive shaft 26 will cause the rollers 40 and 70 to become aligned at right angles to each other except for the "hunting" motion which is attenuated and modified as hereinafter more fully described. As above set forth, rotation of drive shaft 26 causes the shaft 38 to rotate about its axis and hence rotation of the roller 40. Roller 40 being in frictional contact with the rollers 70 causes the latter to rotate together with shaft 66 and roller 72. Rotating of roller 72 on track 74 causes rotation of shaft 24. The rotational speed of shaft 24 is directly related to rotational speed of shaft 26 by a factor, which may be designated by the letter "K." K is a constant determined by the several roller and track diameters and may be expressed as follows, assuming the letter D to designate the various diameters of the shafts and rollers:

$$70 \quad K = \frac{D - 40 \times D - 72 \times D - 50}{D - 48 \times D - 70 \times D - 74}$$

It is evident that when shafts 38 and 66 are not parallel but are at right angles, as illustrated in Figs. 1 and 2, rotation of roller 40 will not cause rotation of the roller 70 but will merely

slip on its surface. This ninety degree displacement between the axial positions of shafts 38 and 66 is the normal position thereof or the position of equilibrium. Rotation of the roller 40, which can only be produced by the rotation of the drive shaft 26, will produce a departure from the ninety degree position of equilibrium so that a component causing a rotation of the roller 10 results and hence rotation of the shaft 24. This component is, of course, equal to the sine of the angle of departure from equilibrium, if the angular position of the shaft 26 be represented by the symbol A and the angular departure of shaft 24 from this position of equilibrium by the symbol b, this relationship may be expressed by one differential equation:

$$dA = \frac{db}{1 - K \sin b}$$

Now it is evident that as shaft 26 is rotated from a position of equilibrium at a uniform speed shaft 24 will tend to follow it. The speed of rotation of shaft 24 will not, however, be uniform since it will gradually increase as the angular departure of shaft 24 from the position of equilibrium increases.

If the direction of rotation of shaft 26 is reversed, the unidirectional clutches formed by springs 60 and 62 will cause roller 40 to continue rotating in the same direction irrespective of its direction of revolution. Shaft 24 will, however, continue to rotate in the original direction until the angle b becomes zero, at which point shaft 24 will reverse its direction of rotation and follow the shaft 26 in the new direction but lagging behind it. In this manner angular oscillations or "hunting" present in the shaft 26, as the direction of rotation thereof is changed are attenuated in the shaft 24. The degree of attenuation obtainable is governed by the factor K as determined by the several roller and track diameters. Small oscillations of the shaft 26 where the angle b never becomes great will result in great attenuations, whereas increased time intervals between reversals of shaft 26 will increase the size of angle b and reduce the amount of attenuation in the shaft 24.

It is further evident from the foregoing that as the average angular position of the shaft 26 is changed shaft 24 will make the same angular change to a new position of equilibrium. The relative effects of the "hunting" in shaft 26 are necessary to bring the shaft 24 to the position of equilibrium.

It is to be noted that there are two positions where the axis of shaft 38 and 66 are ninety degrees from each other. In one of these positions, however, equilibrium does not exist and in this position the rotative effect of the "hunting" in shaft 26 drives the shaft 24 from this position. If this "hunting" continues, shaft 24 will soon rotate 180 degrees to the other position where equilibrium does exist. Therefore, there is no 180 degree ambiguity.

Assuming the various parts of the mounting assembly to be in the relative positions shown in Figs. 1 and 2, rotation of the shaft 26 in one direction results in simultaneous rotational and revolving motion in the roller 40, which revolving motion is in the same direction as the direction of rotation of shaft 26. At the outset of such revolving motion of the roller 40, roller 10 will fail to respond and the rollers will merely slide at their points of frictional contact. As roller 40 is caused to continue to rotate and revolve, roller

10 will start to revolve in the same direction but at a lesser speed than that of roller 40. Such revolving motion in roller 10 will also cause simultaneous rotation thereof through the medium of shaft 66 and roller 72, riding on the circular track 74. If this action continues, roller 10 will follow roller 40 and the axial displacement thereof from roller 40 will gradually decrease until the plane of the axis of rotation of roller 10 is in alignment with the plane of axis of rotation of roller 40. At this point the rollers 40 and 10 will either be rotating in the same direction or in opposite directions, depending upon the initial direction of rotation of the drive shaft 26. If rollers 40 and 10 are rotating in the opposite directions at this point roller 10 will be driven directly by roller 40 and driven shaft 24 will rotate at its maximum speed. Driven shaft 24 may or may not rotate at the same speed as drive shaft 26, depending upon the relative diameter of the various rollers and tracks in accordance with the operation desired.

If the rollers 40 and 10 are rotating in the same direction, at the moment they first reach a relative axial alignment, roller 10 will continue to revolve at a progressively increased speed until it gradually approaches the opposite position of axial alignment. At this point, the rollers 40 and 10 will travel in opposite directions where roller 40 will drive roller 10. Throughout such "hunting" of roller 10 of the correct relative position of alignment with roller 40, the speed of rotation of shaft 24 will gradually increase.

Upon reversal of the direction of rotation of shaft 26, shaft 24 will continue to rotate in the original direction and its speed of rotation will gradually decrease until it reaches a standstill position, whereupon the rotation of shaft 24 will gradually increase in the opposite direction until the angle of displacement of shaft 10 to shaft 40 is again decreased to a minimum and rollers 40 and 74 have the planes of their axis of rotation in alignment. Fig. 5 clearly illustrates through arrows the two directions in which rollers 40 and 10 revolve. In the full line position shown in Fig. 5, these rollers are at right angles and the dotted line position of roller 40 indicates one direction of approach of roller 40 to axial alignment with roller 10.

It is clear, therefore, that the degree of rotation which shaft 26 imparts to shaft 24 is dependent upon the relative alignments of the rollers 40 and 10 and, therefore, continued irregular variations in the direction of rotation of shaft 26 which is transmitted to the shaft 24 will be reduced to a minimum.

Manifestly the assembly just described is adaptable for many uses and susceptible to changes in construction. It is therefore desired to be limited only by the spirit of the invention and scope of the appended claims.

Having thus described the invention, what is claimed as new and desired to be secured by Letters Patent is:

1. A mounting assembly of the character described comprising a rotatable drive shaft; a rotatable driven shaft; and structure operably joining the shafts for transmitting rotative motion from the drive shaft to the driven shaft and capable of progressively increasing the speed of rotation of the driven shaft to a predetermined rate comprising a rotatable roller for each shaft respectively, each roller being mounted for revolving motion about an axis perpendicular to its respective axis of rotation, means responsive

to the rotation of the drive shaft for rotating its roller as the latter revolves, said drive shaft roller being engageable with the driven shaft roller, structure cooperable with the rotative and revolving action of the driven shaft roller for simultaneously rotating and revolving said driven shaft roller, and means responsive to the rotative and revolving motion of the driven shaft roller for rotating said driven shaft.

2. A mounting assembly of the character described comprising a rotatable drive shaft; a rotatable driven shaft; a rotatable roller for each shaft respectively, each roller being disposed for revolving motion about an axis perpendicular to its respective axis of rotation; means responsive to rotation of the drive shaft for rotating its roller as the latter is revolved by the driven shaft, said drive shaft roller being in peripheral, frictional contact with the periphery of the driven shaft roller, structure cooperable with the rotative and revolving action of the driven shaft roller for simultaneously rotating and revolving said driven shaft roller whereby the drive shaft roller seeks a position where the plane of its axis of rotation is in alignment with the plane of the axis of rotation of the driven shaft roller; and means responsive to the rotative and revolving motion of said driven shaft roller for rotating the driven shaft whereby progressively increased speed of rotation of the driven shaft roller as it approaches alignment with the drive shaft roller is transmitted to said driven shaft.

3. A mounting assembly as set forth in claim 1 wherein the rollers are revolvable in either direction and the driven shaft roller is rotatable in either direction whereby progressively increased speed of rotation is imparted to the driven shaft in either direction as the direction of rotation of the drive shaft is altered.

4. A mounting assembly as set forth in claim 2 wherein the rollers are revolvable in either direction, and the means for revolving and rotating the drive roller and the means for rotating the driven shaft are so formed and disposed as to cause the driven roller to seek alignment with the drive roller as the drive shaft is rotated in either direction.

5. A mounting assembly of the character described comprising a drive shaft and a driven shaft, each mounted for rotation in either direction; a roller for each shaft respectively, each roller being rotatable on an axis perpendicular to and revolvable on an axis in substantial alignment with the axis of rotation of its shaft, said rollers being disposed in mutual, peripheral frictional contact and each having structure for imparting rotational movement thereto in response to revolving motion thereof, said shafts being rotatable in either direction whereby the roller of the driven shaft seeks either of two positions

where the plane of its axis of rotation is in alignment with the plane of the axis of rotation of the drive shaft roller in accordance with the direction of rotation of the drive shaft.

5. A mounting assembly of the kind set forth in claim 5 wherein the drive shaft roller has means for limiting its rotation to one direction whereby the speed of rotation of the driven shaft is progressively decreased to a stationary position and its speed of rotation is then progressively increased to a predetermined rate in the opposite direction as the direction of rotation of the driven shaft is reversed.

10. A mounting assembly of the character described comprising a rotatable drive shaft; a driven shaft mounted for rotation in spaced relation to and in substantial axial alignment with the drive shaft; a roller for each shaft respectively, disposed between the proximal ends of the

15. shafts and each being rotatable on an axis perpendicular to and revolvable on an axis in substantial alignment with the axes of rotation of the shafts; structure joining the drive shaft and its roller and responsive to rotation of the drive

20. shaft in either direction for revolving the drive shaft roller in like directions respectively; means for yieldably holding the rollers in mutual, peripheral, frictional contact whereby revolving motion of the drive shaft roller in either direc-

25. tion imparts revolving motion to the driven shaft roller in corresponding directions; means re-

30. sponsive to the revolving motion of the drive shaft roller for rotating the same, said last men-

35. tioned means having structure for limiting the rotation of the drive shaft roller to one direc-

40. tion whereby the driven shaft roller is caused to seek at a progressively increasing rate of revolution either of two positions where the planes of the axes of rotation of the rollers are in align-

45. ment and where the drive roller rotates the driven roller; and structure for transmitting said progressively increased rate of revolution into proportionate progressively increased rate of rotation in the driven shaft.
